(57) **CLAIM**

The ornamental design for a voltage and temperature collecting assembly for power battery as shown and described.

DESCRIPTION

FIG. 1 is a bottom, front and right side perspective view of a voltage and temperature collecting assembly for power battery showing our new design;

FIG. 2 is a top, rear and left side perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2; and,

FIG. 12 is an enlarged view of portion 12 in FIG. 2.

The broken lines in the drawings illustrate portions of the voltage and temperature collecting assembly for power battery which form no part of the claimed design.
